UNITED STATES PATENT OFFICE.

HOKAN LUDVIG LARSON, OF CHILLIWACK, BRITISH COLUMBIA, CANADA.

DREDGE.

Application filed February 10, 1925. Serial No. 8,268.

To all whom it may concern:

Be it known that I, HOKAN LUDVIG LARSON, a subject of the King of Great Britain, and a resident of the city of Chilliwack, in the Province of British Columbia, Canada, have invented certain new and useful Improvements in Dredges, of which the following is a specification.

My invention relates to improvements in dredges the objects of which are to provide means whereby the dredge bucket may be conveniently tipped to discharge its load for delivery, and also to provide means whereby the bucket may be operated at an angle to the longitudinal line of the dredge.

The invention consists essentially of a pair of pontoons or supports upon which a frame is carried and a pivotally mounted bucket suspended beneath the frame, which is adapted to be lowered vertically to the bed of the stream or working and then swung forward to collect dirt and gravel therefrom, as will be more fully described in the following specification, in which:

25 Fig. 1 is a longitudinal section of the dredge.

Fig. 2 is an end view.

Fig. 3 is a plan view.

30 Fig. 4 is a perspective view showing the dredge bucket and its bridle.

Figs. 5, 6 and 7 are views of the bucket in various swinging and tipping positions.

Fig. 8 is a front view of the cross arm and bale from which the bucket is suspended.

35 Fig. 9 is a plan view of same showing the bale swung at an angle.

In the drawings like characters of reference indicate corresponding parts in each figure.

40 The numeral 1 indicates a pair of pontoons or skids which are spaced apart and are suitably braced by cross members 2 and 3, and supports a working platform 4. Forward of the platform a pair of standards 5

45 are erected which are cross connected at their upper ends by a head 6 for the purpose of carrying the bucket. At the rear of the platform 4 further supports 7 are erected to carry cross members 8 and 9. A pair of beams 10 extend between opposite ends of the head 6 and the cross member 9 which in turn carry a cross beam 11, the purpose of which will appear later. A cross head 12

is mounted between the standards 5 which is adapted for adjustment therealong and 55 which is held in any desired position by a pair of pins 13 extending through the standards, such cross head serving as a bumper to indicate, by the increased weight on the hoisting ropes, when the bucket has been 60 raised to the desired height.

The numeral 14 is a sliding crosshead mounted between the standards 5 which is limited in its downward movement by a pair 65 of pins 14^a set at any desired position in the standards, and from which is pivotally suspended as at 15, a bale 16. A rope 17 leads from a drum 18 of a winch 19 over a sheave 20 mounted under the head 6, and extends downwards to a point adjacent the upper 70 side of the crosshead 14 where it is divided to form a bridle 21 which extends through the sliding crosshead and is attached at its outer ends to the bale 16 on opposite sides of the pivot 15, so that the bale is restored 75 to parallel position with respect to the crosshead on being drawn up after operating the bucket at an angle from its normal suspended position (see Fig. 9).

The numeral 22 indicates generally a 80 dredging bucket having a bottom wall 23, a rear wall 24, side walls 25 and a front wall 26. On the upper edge of the front wall 26 a plurality of prongs 27 are provided to disturb the material to be raised by the 85 bucket. The bucket is suspended from the bale by a pair of connecting rods 28 pivotally connected at their upper ends to the bale 16 and at their lower ends to the bucket by a pair of trunnions 29. A pair of stops 30 are provided adjacent the upper front edge of the bucket side walls 25 for the purpose of preventing the bucket from tilting beyond 90 a predetermined angle as shown in Figure 7.

As a means for drawing the bucket in a 95 forward direction after being lowered to the bed, a rope bridle 31 is attached to the bucket adjacent the stops 30 and connected to a line 32 leading through a sheave 33, hooked onto one of the eye bolts 34 or 35 thence through a sheave 36 under the head 6 and onto a drum 37 of the winch 19. The numeral 38 indicates an inclined track supported between the cross members 8 and 11 and upon which a carriage 39 having a counterweight 100 105 40 is adapted to run, the carriage is further

provided with a sheave 41, the purpose of which will hereinafter appear. A bridle 42 having connection with the bucket 22 or connecting rods adjacent the trunnions 29 5 and also at the forward edge of the bottom wall 23 is provided for the purpose of drawing the bucket rearwardly and into tipping position, the bridle having a running connection through a ring 43 with a tipping line 44 which is led through the sheave 41 up and through a further sheave 45 at the upper extremity of the track 38 and around a drum 46 of the winch 19.

It will be noted that the pull of the tipping line 44, when the counterweight 40 is 15 in normal position or at rest, is effected on the bucket at a point above its vertical centre (see Fig. 5) so that the bucket is kept in line with its connecting rods 28. As the 20 pull is increased and the bucket is swung out of the vertical, the counterweight is raised along its inclined track 38, the line of pull being exerted at a lower level on the bucket to correspond with the raising of the 25 counterweight while still maintaining the bucket in parallelism with its connecting rods (see Fig. 6). As the pull is increased the counterweight is drawn to the upper end of its track as shown in dotted line in Figure 1, the bridle 42 becoming so disposed about the bucket as to exert a pull below its vertical centre thus tipping the bucket to discharge its contents. As a means for insuring the tipping of the bucket in the event 30 of its being but lightly loaded and its centre of gravity being below the lowest line of pull of the tipping line, a stop 47 is provided which arrests the rearward swing of the connecting rods 28 and causes the entire 35 pulling force to be exerted upon the bucket below its pivotal point.

Having thus described the several parts of my invention I will now briefly explain its operation.

40 The dredge is moved into position over the ground to be dredged and the bucket 22 lowered by unwinding the line 17 off the drum 18, when it has reached the bed to be dredged it is turned over to present its digging prongs 27 to the gravel and is drawn forward by winding in the line 32, the bucket is then raised, when the release of tension on the line 32 allows it to assume a vertical position. When the bucket is raised to the 45 desired height it is drawn rearward and tipped to discharge as hereinbefore described.

What I claim as my invention is:

1. In a dredge having a pair of vertical 50 standards and a head, of a crosshead slidable along the standards, a dredging bucket suspended for swinging movement below the crosshead, means for lowering and raising the crosshead and bucket for upsetting and drawing the bucket forward to fill and after

filling to restore the bucket to normal position, and means for inverting the bucket to discharge after raising.

2. In a dredge having a pair of vertical standards and head, of a crosshead slidable 70 along the standards, a dredging bucket suspended for swinging movement below the crosshead and normally adapted to dredge at right angles to the crosshead, means for drawing the bucket forward to fill at a 75 tangent to the crosshead, means for lowering and raising the crosshead and bucket, means for aligning the bucket with the crosshead when raising, and means for inverting the bucket to discharge after raising.

3. In a dredge having a pair of vertical standards and a head, of a crosshead slidable along the standards, a bale pivotally connected below the crosshead, connecting rods swingingly connected to opposite ends 80 of the bale and pivotally carrying a dredging bucket, a line for lowering and raising the crosshead and bucket and a bridle connecting said rope and bale and passing through the crosshead whereby the bale may 85 be swung out of parallelism with the crosshead and such parallelism restored by the tension of the crosshead upon the line.

4. In a dredge having a swinging bucket adapted for lowering and raising, said 90 bucket being pivotally mounted on trunnions between connecting rods and normally hanging in line therewith and single means for swinging the bucket and the connecting rods as a unit within a predetermined arc 100 and for tipping to discharge the bucket about its trunnions when the normal length of the arc is exceeded.

5. In a dredge having a swinging bucket adapted for lowering and raising, said 105 bucket being pivotally mounted on trunnions between connecting rods and normally hanging in line therewith, of a bridle one end of which is connected beneath the bucket and the other end adjacent to the trunnions, 110 and a hauling line runnably connected to the bridle that the initial pull is exerted above the centre of gravity of the bucket and the final pull is exerted below the centre of gravity to tip it about its trunnions.

6. In a dredge having a swinging bucket adapted for lowering and raising, said 120 bucket being pivotally mounted on trunnions between connecting rods and normally hanging in line therewith, of a bridle one end of which is connected beneath the bucket and the other end adjacent to the trunnions, and a hauling line connected to the bridle, 125 said hauling line being adapted to raise a counterweight as the pull thereon is increased to alter the height of the pull upon the bridle and to tip the bucket when a predetermined point is reached.

7. In a dredge having a swinging bucket adapted for lowering and raising, said 130

bucket being pivotally mounted on trunnions between connecting rods and normally hanging in line therewith, of a bridle one end of which is connected beneath the bucket and the other end adjacent to the trunnions, and a hauling line connected to the bridle, an inclined track having a counterweight movable therealong, said line being lead

from the bridle to a sheave upon the counterweight thence over a sheave at the upper 10 end of the inclined track and from thence to a winding drum.

Dated at Vancouver, B. C. this 24th day of January, 1925.

HOKAN LUDVIG LARSON.
